UNITED STATES PATENT OFFICE

2,279,005

DOOR CONSTRUCTION

Kenton D. McMahan, Schenectady, N. Y., assignor to General Electric Company, a corporation of New York

Application March 30, 1939, Serial No. 264,990

5 Claims. (Cl. 189—46)

My invention relates to a door construction, and in particular to door sealing means for use with fluid tight doors.

It is an object of my invention to provide a new and improved quick-opening, fluid-tight door which is rugged in construction, positive in operation, and inexpensive of manufacture.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a perspective view partly in section illustrating an application of my invention; Fig. 2 is an enlarged partial sectional view of the door construction shown in Fig. 1 taken along the line 2—2 of Fig. 1; and Fig. 3 is an enlarged sectional view of a detail of the invention illustrated in Figs. 1 and 2.

I have provided a door 10 comprising two elements 11 and 12 arranged to telescope one into the other with a space 13 between the elements 11 and 12 at the periphery thereof. The spacing between the elements 11 and 12 may be controlled by suitable mechanism in response to the operation of hand wheels 14. Within the space 13 is placed a buckling strip or deformable band 15 of resilient material, such as rubber, which may be eccentrically loaded. For example, a groove 16 may be provided in the inner face of the strip 15. When the strip or band 15 is compressed by the telescoping of the elements 11 and 12, as best shown in Fig. 3, the groove 16 causes an eccentric loading of the band which in turn causes the band to buckle and engage the doorway 17 in the wall 18 and seal the space between the door 10 and the doorway 17. With this arrangement accurate machining is unnecessary because, due to the manner of loading the band 15, a good seal is obtained even though the clearance between the door and the doorway varies over a wide range.

Describing my invention in greater detail, the element 11 of the closure member or door 10 may be formed of a plate, generally oval in shape, having a laterally extending flange 19 integral therewith. The second element 12 is shown in the form of a generally oval-shaped shell having an outwardly directed flange 20 formed integral therewith. The element 12 is so dimensioned that it will fit into and slide within the flange 19 in telescopic relation therewith.

The flanges 19 and 20 may be conveniently manufactured separately of the elements 11 and 12 and welded or otherwise suitably secured in the proper position, to the elements 11 and 12. 5 From Fig. 2 it will be seen that the flanges 19 and 20 provide a space 13 between the elements 11 and 12 for the reception of a buckling strip or band 15 preferably of resilient material such as rubber. The band or strip 15 is shaped to be deformed in cross section, as by assuming a different cross sectional shape, and to yield laterally by bending at a particular location when force is applied to the edges of the band 15. As shown in the drawing, strip 15 is provided with a longitudinally extending groove 16 in its inner face to insure buckling toward the doorway 17 when sufficient force is applied to the edges thereof by elements 11 and 12. I have provided suitable means to control the length of the space 13 and therefore the load or buckling force applied to the band 15. In the illustrated embodiment of my invention two sets of length controlling or force applying means are provided. Inasmuch as the construction of each is the same, only one will be described. A block 21, having an opening 21a therethrough, is secured to the outside of the element 11 as by welding for example. An opening 22 is also provided in the member 11 in alignment with the opening 21a in the block 21. A support 23 in the form of an angle may be suitably secured to the element 12 and is provided with an opening 24 in alignment with the openings 21a and 22. A rod 25 threaded at both ends is projected through the above-described openings. A hand wheel 14 threadingly engages each end of the rod 25. Pins 26 extending through rod 25 are provided to prevent the hand wheels 14 from unscrewing sufficiently to drop off the rod 25. 10 In order to seal the opening 22 through the element 11, I provide sealing or packing material 27 around the rod 25 and a gland 28 to compress or squeeze the packing 27, the squeezing force being transmitted from the hand wheel 25 to the gland 28 through a washer 29. In order to prevent rotation of the rod 25, I have provided a pin 30 suitably secured to the support 23 and projecting into a slot 31 formed in the rod 25. The slot 31 has a sufficient length to permit free movement of elements 11 and 12, but to prohibit any substantial rotation of the rod 25. I have found that in some cases the pressure of the packing 27 on the rod 25 is sufficient to prevent rotation thereof, in which case the pin 30 and slot 31 may be omitted. 15 20 25 30 35 40 45 50 55

A suitable means for loosely hinging the door 10 in the doorway or closure frame member 17 is illustrated in Figs. 1 and 2. As shown, the door is carried by a frame 32 comprising horizontal members 33 and a diagonal member 34 suitably secured at the ends thereof to the horizontal members 33 in any suitable fashion. As best shown in Fig. 2, one end of each member 33 is provided with a pivot in the form of a screw 35 which threadingly engages a tapped hole in the member 33 and enters a suitable bore 36 in the block 21. This arrangement permits vertical adjustment of the door 10, a locking nut 37 being provided to lock the screw 35 in the desired position. The other ends of the members 33 are suitably pivotally secured to blocks 38 which in turn are secured to the wall 18 in any desired manner, as by welding. This construction is advantageous in that the door 10 is permitted to move in substantially a straight line until the door 10 clears the doorway 17 before there is any substantial sidewise or turning movement.

When force is applied to the edges of the resilient buckling strip 15 due to the telescoping action of elements 11 and 12 as when one or more of the hand wheels 14 are tightened, the strip 15 will buckle or bend outwardly along the entire periphery of door 10 to assume the shape illustrated in Fig. 3, thus sealing the opening between door 10 and doorway 17. Just after elements 11 and 12 are forced into engagement with strip 15 substantially all the force will be effective to bend or buckle the strip 15 laterally lengthwise of the strip, and there will be little if any compression of the strip 15. After the strip 15 has bent into sealing engagement with the doorway 17 there will be some compression of strip 15 transversely thereof, this compression force added to the increased buckling force tending to press the strip 15 more securely against the doorway 17. Thus, the greater the force tending to telescope the elements 11 and 12, the tighter will be the seal between the doorway 17 and the door 10. Due to the resiliency of the band 15, when the buckling force is removed the band 15 tends to spring back or return to its unstressed position, this force tending to separate the elements 11 and 12 to release the door 10.

Many modifications of the above construction are possible. For example, whereas I have illustrated the use of a resilient rubber band 15, any resilient material which can be eccentrically loaded may be used. For instance, a strip of resilient metal, as spring steel, may be used. Furthermore, the eccentric loading may be obtained in other ways than by grooving the inner face of the band. For example, the band or strip 15 may be deformed or bent in some suitable manner as by providing a band arcuate or crescent-shaped in cross-section. The important thing is to shape or deform the strip 15, as by providing unequal cross-sectional areas on each side of an axis extending through the line of action of the means engaging each side of the strip whereby the strip is eccentrically loaded in such a manner as to insure buckling or yielding toward the doorway 17. While a door substantially oval in shape has been shown, any desired shape may be employed, and this type of door may be used in connection with any type of a wall or doorway construction. Other means of supporting and hinging the door will be apparent, and any number of hand wheels may be employed. More-

over, the sealing means may be supported on the doorway, the resilient member bending into engagement with the door, if desired.

While I have shown and described my invention in connection with a specific arrangement thereof, I do not desire my invention to be limited to the specific arrangement shown and described, and I intend in the appended claims to cover all the modifications within the spirit and scope of my invention.

What I claim as new and desire to secure by Letters Patent of the United States, is:

1. A fluid-tight closure construction comprising a wall having an opening therein, a closure frame member about said opening, a closure member for said opening, a resilient strip extending around the periphery of one of said members, said strip having a longitudinally extending groove on the surface presented to said one of said members and means engaging said strip for causing said strip to buckle at said groove into fluid-tight engagement with the other of said members.

2. In combination a wall having an opening therein, closure means for said opening, a resilient strip extending around the periphery of said closure means and having a longitudinally extending groove on the inner surface thereof, and means engaging said strip for causing said strip to buckle at said groove into fluid-tight engagement with the edge of said opening.

3. In combination a wall having a doorway therein, closure means for said doorway comprising a first element and a second element, said elements being telescopically arranged with respect to each other, a peripheral space between said elements, a resilient band in said peripheral space, said band having a longitudinally extending groove on the inner face thereof, and means to telescope said first and second members into engagement with said band for causing said band to bend outwardly at said groove into fluid-tight engagement with said doorway to seal the opening between said door and said doorway.

4. A fluid-tight closure construction comprising a wall having an opening therein, a closure frame member about said opening, a closure member for said opening, a deformable resilient longitudinally extending strip carried by one of said members, and means engaging said strip at each side thereof for compressing said strip and causing said strip to bend laterally by buckling into sealing engagement with the other of said members, said strip having a cross section of such character that said strip is eccentrically loaded when subjected to said compressing force when applied at each side by said engaging means.

5. A fluid-tight closure construction comprising a wall having an opening therein, a closure frame member about said opening, a closure member for said opening, a deformable resilient longitudinally extending strip carried by one of said members, and means engaging said strip at each side thereof for compressing said strip, said strip having unequal cross-sectional areas on each side of an axis extending through the line of action of said engaging means whereby said strip is eccentrically loaded and caused to bend laterally by buckling into sealing engagement with the other of said members when subjected to the compressing forces applied along said sides by said engaging means.
